ADRIAAN FREDERIK VAN AMSTEL, OF AMERSFOORT, NETHERLANDS.

LIQUID PUMP.

Application filed November 18, 1920. Serial No. 424,956.

To all whom it may concern:

Be it known that I, ADRIAAN FREDERIK VAN AMSTEL, a subject of the Queen of the Netherlands, residing at Amersfoort, in the 5 Province of Utrecht, in the Kingdom of the Netherlands, have invented certain new and useful Improvements in Liquid Pumps; and I do hereby declare that the following is a full, clear, and exact description of the same.

10 This invention relates to a liquid-pump for internal combustion engines and is characterized in that the discharge or outlet valve of the pressure space of the pump is not hydraulically but mechanically opened 15 inwards with respect to said pressure space, and that the operation of opening the outlet valve is performed in the interior of the pump by means of the pump piston or plunger or diaphragm or other liquid-displacing- 20 member.

The pump according to the invention is principally designed for injecting liquid fuel or water into the combustion space of internal-combustion engines, and also may 25 serve for other purposes.

The pump may be constructed in such a way, that during the pressure stroke of the same, the liquid fuel is first compressed in the pressure space of said pump, i. e., is 30 brought under pressure, before the outlet valve, at a certain point of the pressure stroke, is mechanically opened; and that the valve has returned into position on its seat before the pressure stroke is terminated. 35 By this arrangement the injection into the motor is properly timed and the liquid in the pump from the beginning to the end of the injection into the motor stands under a high pressure. When desired the injection 40 may take place in a very short time, or it may be prolonged for some time, namely, whilst the crank of the engine travels through a larger angle, and in both cases it may take place powerfully and with a 45 high speed, without putting too high requirements upon the pump or its driving means. Moreover the injection may be effected with approximately constant pressure, by choosing the dimensions in such a 50 manner, that the liquid-displacing-member, during the injection, displaces a quantity of liquid nearly equal to that discharged by the outlet valve. Also the dimensions may be such, that during the injection, the

pressure in the pump is increased or decreased. 55

Another embodiment of the invention consists in that the outlet valve is closed after the pressure stroke of the pump has been completed. 60

In many internal-combustion engines the fuel must be injected under a high pressure in less than one fiftieth of a second and for this object the member driving the pump, in case the latter is of the ordinary known 65 construction, has to operate the pump piston with such tremendous speed and force, that the operation is practically equivalent to producing hundreds of hammer blows per minute. In the case of ordinary low-com- 70 pression engines with surface ignition, pressures in the pump barrel of 125 atmospheres and over have been registered, so that it will be clear what exceedingly high requirements 75 said pumps and their driving mechanism have to fulfil if such a pressure has to be produced hundreds of times per minute and each time in one fiftieth of a second or even less. In the case of a pump according to the invention such pressure and even 80 higher ones can be obtained with the same or still higher frequency, without unduly stressing the pump and the driving mechanism. It is not necessary that the liquid-displacing-member is operated with a high 85 speed, since the pressure stroke of the pump may start a considerable time before the starting of the injection. In order to render this possible, without producing too high a pressure in the pump, the pressure space 90 of said pump is chosen so large, that in it the liquid may be sufficiently compressed. For this object the pressure space of the pump need not to be inconveniently large, since for each power stroke only a small 95 quantity of liquid is injected and the compressibility of the liquid is sufficient. If desired the dimensions may therefore be so chosen, that the liquid-displacing-member, displaces more liquid after the beginning 100 of the active part of the pressure stroke than is injected into the motor. A portion of the liquid displaced therefore remains in the pressure space and again expands during the return stroke or suction stroke 105 of the liquid-displacing-member.

Pumps are known, with which, as is the case with a pump according to the inven-

tion, by mechanically opening the outlet member, sufficient pressure already prevails in the liquid, to obtain a powerful injection into the engine immediately when said outlet member is opened, and in said pumps the outlet member may be again closed, when a high pressure still prevails in the pressure space of the pump. This outlet member is however a slide, along which liquid is liable to leak and said slide is actuated from outside the pressure space of the pump so that the device is moreover not so simple as that according to the invention and also lacks other advantages obtained therewith.

15 In order that the invention may be better understood, it is hereinafter further described with reference to the accompanying drawings, which show, by way of example, a few embodiments of the invention and 20 are not drawn to scale.

Fig. 1 shows, partly in section, a part of an engine, provided with a pump according to the invention.

25 Figs. 2 and 3 are detail views showing parts of the pump according to Fig. 1.

Figs. 4, 5 and 6 are detail views showing parts of the pump shown in Fig. 1, said parts being placed in different operative positions.

30 Fig. 7 shows a modification of the parts according to Figs. 4, 5 and 6.

Figs. 8, 9, 10, 11 and 12 are detail views relating to a construction, in which the pump piston lifts the outlet valve by means 35 of a bell crank lever pivotally secured to said valve.

Fig. 13 shows a part of a pump plunger, which lifts the outlet valve by means of a pawl, pivotally secured to said outlet valve.

40 Fig. 14 shows, partly in section, a pump, the outlet valve of which returns in position on its seat after the pressure stroke is completed.

Fig. 15 is a section on the line A—B in 45 Fig. 14 of the lifting member secured to the lower end of the outlet valve.

Fig. 16 illustrates, partly in section, another embodiment of a pump, the outlet valve of which is closed after the termination 50 of the pressure stroke.

The engine cylinder 1, the water jacket 2 and the cylinder head 3 in Fig. 1 are integral with each other. The pump casing 4 is attached in and on the cylinder head 3 by 55 means of bolts (not shown in the drawing) or in any other suitable way. The outlet valve 5 of the pump is at the same time the injection needle of the engine and the lifting member 6 is also the pump piston. By 60 means of the pipe 7 the casing 4 is in open communication with the vessel 8, in which the suction valve 9 is arranged. The exact dimensions of the pressure space can therefore be obtained by choosing the dimensions 65 of the vessel 8 accordingly. The advantage

obtained by the provision of this separate part 8 of the pressure space of the pump is that the casing 4 may be small and occupies little room in and on the cylinder head, not only because the supplementary pressure 70 space is found in the vessel 8, but moreover since in the latter also the suction valve 9 may be arranged. The vessel 8 may be arranged at a suitable place out of the way. On the valve 5 the valve head 10 is arranged, 75 in which head, a forked member 12 is pivotally disposed by means of shaft 11. Between the shanks of the forked member 12 a roller 13 is located, which is rotatable about the shaft 14, the ends of which latter 80 project into corresponding holes in the fork shanks. The pump piston 6 is not rotatable and is provided with a cam 15. The supply duct 16 is preferably connected with a tank, in which the level of the liquid is above that 85 of the by-pass 17, so that the pressure space of the pump is filled by gravitation and the air escapes from the pump through the passage 17. Before putting the pump into action, the suction valve 9 is opened by means 90 of the rod 18, and also the stop valve 19 is opened. Fig. 2 is a sectional plan view of the valve head 10, this section being taken through the centre of the bearings of the shaft 11 for the forked pressure member and 95 Fig. 3 is a section of the forked member 12 and the roller 13, going through the centres of the bores of the shafts 11 and 14, and also an elevation of said shafts. The moving parts are shown in Fig. 1 in the position 100 100 which they occupy when the active part of the pressure stroke starts. During the first part of this active part of the pressure stroke the liquid is compressed in the pressure space of the pump, in consequence whereof the 105 pressure increases. As soon as the cam 15 abuts against the roller 13 (see Fig. 4) the opening of the valve 5 starts, since the piston 6 continues its movement and the forked member 12 rests against the pump casing 4, 110 so that it is prevented from turning to the right (in anti-clockwise direction). The forked member 12 is therefore sliding on the pump casing 4, pressed upwards by the cam 15 together with the valve head 10 and the 115 valve 5 until the valve has been fully lifted (see Fig. 5). After the position shown in Fig. 5 has been reached, the forked member 12 tilts to the left (rotating in clockwise direction) by the pressure of the valve spring 120 20 and the valve 5 is closed. Since the pump piston 6, whilst the valve 5 is open, continues its pressure stroke and the sectional area of the valve seat and of the jet passage 21 is sufficiently small, at the moment in which 125 the valve 5 is closed, a pressure still prevails in the pump, higher than that in the engine cylinder 1, so that the injection is effected powerfully and rapidly up to the end; and the jet collides violently against the collision 130

member 22, resulting in a dispersion of the fuel in extremely small globules into the engine cylinder. The position occupied by the pump piston 6 and the forked member 12 after the latter has been tilted, i. e., when the valve 5 is again upon its seat, is shown in Fig. 6. Soon afterwards the motion of the piston 6 is reversed and its suction stroke starts. As soon as the cam 15 permits, the forked member 12 is turned to the right by the spring 23 (in anti-clockwise direction), till it rests again on the casing 4, as is the case in the Figures 1, 4 and 5. During the first part of the suction stroke the liquid in the pressure space of the pump expands, till the pressure in the supply duct 16 opens the suction valve 9 and a quantity of fuel is again drawn into the pressure space. The quantity of fuel, injected into the motor through the jet opening 21, during the opening of the valve 5 may be controlled in a well known manner by the governor of the engine, by hand or in both ways, e. g., by variably limiting the suction stroke of the piston 6 or by keeping the suction valve 9 open during a shorter or longer part of the pressure stroke, so that a portion of the fuel flows back from the pump into the supply duct 16 or by both means. (If the suction valve 9 is held open during a part of the pressure stroke, the active part of the pressure stroke begins when the suction valve is closed.) In case the limits of the control are not sufficiently spaced apart to attain the desired object, the volume which the pressure space of the pump is able to contain may be varied by inserting or removing balls 24 into or from the vessel 8. If more balls are inserted into the vessel, so that the liquid capacity of the pressure space of the pump is decreased, then the pressure in the pressure space of the pump is raised higher, the compressibility of the liquid and the displacement caused by the piston 6 remaining unaltered, in consequence whereof during the opening of the valve 5 more fuel is shot from the pump into the engine. On the other hand, by removing one or more balls 24 from the vessel 8, a smaller quantity of fuel is injected.

In Figure 7 a modified form of the pump piston 6 and the bifurcated member 12 is illustrated. In the case of the construction shown in Figure 1, the centre of the shaft 11 of the forked member 12 lies at the right of the imaginary perpendicular line through the centre of the roller shaft 14, in consequence whereof the forked member turns to the left immediately, when the valve is fully lifted, but in the case of the construction shown in Figure 7 the centre of the shaft 11 lies at the left of the imaginary perpendicular line through the centre of the roller shaft. Moreover the upper part of the cam 65 is horizontal, so that the valve 5 is kept open for some time on the same lifting height, whilst the piston continues its pressure stroke. In Figure 7 the piston and the forked member are shown in the position, which they take at the moment in which the forked member is on the point of tilting to the left (rotating in clockwise direction). Due to the tilting of the forked member 12 to the left, the valve 5 is closed, as is the case with the embodiments shown in Figures 1-6. The modified form shown in Figure 7 may serve, if the period of injection has to be prolonged and if desired the sectional area of the seat of the valve 5 and of the jet passage 21 may be so chosen that the piston 6, while the valve is open, displaces a quantity of fuel, approximately equal to that emerging through the valve, when the engine runs under full load, so that the injection from beginning to the end takes place with substantially constant pressure. Such an injection may, e. g., be desirable in the case of constant-pressure (Diesel) engines. It is obvious, that also the sectional area of the seat of the valve 5 and of the jet canal 21 may be made smaller or larger, so that the pressure of injection during such injection rises or falls.

The Figures 8, 9, 10, 11 and 12 relate to a pump, in which the valve 5 is lifted by the piston 6 by means of a bell crank lever 26 secured to the valve head 10 and pivotally mounted on the shaft 25. In Figure 8 the piston 6, the bell crank lever 26 and the valve head 10 are shown in the position, which they take at the beginning of the pressure stroke; and Figure 9 is an elevation of the piston and the bell crank lever with the shaft 25, seen from the right. The left arm 27 of the bell crank lever rests upon the piston and its right arm 28 has a groove made therein (see Figure 9) through which a ridge 29 formed on the piston is adapted to reciprocate. The ridge 29 serves to keep the left arm 27 on the level of the lifting edge 110 of the piston 6, when said edge, as is the case in the position shown in Figure 8, is at the left of the arm 27. During the active part of the pressure stroke, the liquid in the pressure space of the pump is first compressed so that the pressure is raised. As soon as the lifting edge of the piston abuts against the right arm 28 of the bell crank lever (see Figure 10) the opening of the valve 5 starts. The continued motion of the piston causes the lifting of the valve 5 till the lower end of the arm 28 has reached the upper face of the lifting edge of the piston (see Fig. 11). As soon as this has taken place the lever 26 rapidly turns to the left (in clockwise direction) by the pressure of the valve spring 20, so that the valve 5 is closed. In Figure 12 the position is shown which the piston and the lever take after the valve is closed. Soon afterwards the motion

of the piston is reversed and as soon as the lifting edge of the piston allows the arm 28 to pass, the spring 30 presses the bell crank lever back in its position shown in Figures 5 8, 9 and 10. The distance indicated by the arrows is therefore the same in the Figures 8, 10 and 12, but in Figure 11 it is increased by the lift of the valve 5.

In the design according to Figure 13 the 10 valve 5 is lifted by the piston 6 by means of a tooth 32 pivotally mounted on the shaft 31 in the valve head 10. The piston and the tooth are shown in the position, which they take, when, during the pressure stroke, the 15 piston starts to turn the tooth to the right (in anti-clockwise direction). Somewhat later during the pressure stroke the tooth abuts against the stepped lifting edge of the piston and the valve is lifted until the lower 20 face of the tooth comes free from the lifting edge of the piston and the valve 5 is closed. Thereupon the motion of the piston 6 is reversed and as during the suction stroke the lifting edge of the piston has 25 passed sufficiently far to the left, the tooth is turned by the spring 33 to the left (in clockwise direction) till it abuts against the stop 34, formed on the valve head 10, this being the position shown in Figure 13. The spring 30 33 is fastened to the pin 35 provided within the valve head 10.

In the case of the pump shown in Figure 14 no separate vessel 8 is used and the suction valve 9 is located in the pump casing 35 4. In the valve head 10 a roller 36 is provided, the upper face of which lies in the path of the cam 15 formed on the piston. The outlet valve 5 is lifted at the termination 40 of the pressure stroke and returns to its seat after the motion of the piston has been reversed, i. e., after the beginning of the suction stroke. This pump may serve inter alia for engines, in which the pump is not placed on the top of the cylinder, as is the case with the pump according to Figure 45 1. The fuel is supplied to the engine through the pressure passage 37. If the orifice of said passage leading into the engine is continuously open and in the conduit 50 no non-return valve is applied, the liquid in the passage, after the injection is terminated, is somewhat withdrawn by the piston 6 and does not remain in the forepart of the passage. Thereby the fuel is prevented from 55 afterflowing into the cylinder when during the power stroke of the engine, the pressure in the cylinder sinks so that the liquid in the passage 37 expands and the walls of the passage contract. It is obvious that in 60 this way the injection into the engine does not take place up to the end under a high pressure. This pressure in the pump sinks during the opening of the outlet valve 5, until it is equal to the pressure in the engine 65 cylinder. The injection may however start

under a high pressure. The initial pressure may be increased or decreased by inserting or removing one or more balls 24 into or from the plug 38. Figure 15 is a section of the valve head 10 on the line A—B in Figure 70 14. Of course the pump may also be provided with a stop valve 19 with an outlet passage 17, as is the case with the pump according to Figure 16.

As may be understood, a pump, in which 75 the liquid is passed from the pump into a passage 37, as is the case with the pump according to Figure 14, may also be provided with one of the arrangements above described in order that the outlet valve 5 may 80 be closed before the end of the pressure stroke.

The pump shown in Figure 16 differs 85 from that according to Figure 14 in that the piston does not lift the valve 5 by means of a roller, but by means of a lever 39. At the end of the pressure stroke the piston 6 first presses the right arm of the lever 39 upwards, till said lever abuts against the suction valve 9 and the continued motion of the 90 piston 6 causes the valve 5 to open. The valve 5 returns to its seat by the tension of the spring 20, as soon as the piston 6, after the starting of its suction stroke, has sufficiently sunk. The valve 5 may also be 95 opened by the suction valve 9 by pressing the rod 18 downwards. This may be of advantage, to fill the pressure space of the pump and the passage 37 with liquid, before the 100 pump is taken into use.

In all the embodiments described the stop valve 19 and the suction valve 9 may be opened, even while the engine is running, to let the air escape from the pump. In this case it is necessary to stop the motion 105 of the liquid-displacing-member 6, or to shorten its pressure stroke, in such a way, that it does not lift the outlet valve 5. In the case of the designs according to Figures 1—13 for this purpose also the suction stroke 110 of the member 6 may be so abbreviated, that the forked member 12, the lever 26 or the tooth 32, cannot turn over such a distance that they take the position, which would cause the outlet valve 5 to be lifted during 115 the pressure stroke. It is necessary that the outlet valve 5 remain closed when the stop valve 19 and the suction valve 9 are opened, since otherwise air might pass from the engine cylinder through the valve 5 into 120 the pump. If in the case of the pumps shown in figures 14 and 16 a check valve is applied in the conduit 37, it is obvious that it is not necessary to eliminate the opening of the discharge valve 5 when the stop valve 19 is opened for the purpose of letting out air from the pump pressure space.

What I claim is:

In a liquid-pump, in combination, a receptacle adapted to provide a pressure cham- 130

ber therewithin, a discharge valve for said pressure chamber adapted to be opened toward the inside of said pressure chamber, a liquid-displacing-member adapted to put the liquid under pressure in said pressure chamber while said discharge valve is closed, and means adapted to mechanically transmit

within said pressure chamber, part of the motion of said liquid-displacing-member to said discharge valve for opening the same. 10
In testimony whereof I hereto affix my signature.

ADRIAAN FREDERIK van AMSTEL.
